UNITED STATES PATENT OFFICE.

ANDREW POULSON, OF HOUGH GREEN, NEAR WIDNES, AND WILLIAM CHARLES AUGUSTUS MATE, OF GARSTANG, ENGLAND, ASSIGNEES TO CHARLES JOSEPH ROURKE, OF CHEADLE HULME, MANCHESTER, ENGLAND.

SMELTING FURNACE OR CUPOLA.

1,311,711.

Specification of Letters Patent. Patented July 29, 1919.

Application filed October 15, 1917. Serial No. 196,751.

To all whom it may concern:

Be it known that we, ANDREW POULSON and WILLIAM CHARLES AUGUSTUS MATE, subjects of the King of Great Britain, and 5 residents of Hough Green, near Widnes, England, and Garstang, Lancashire, England, respectively, have invented certain 10 new and useful Improvements in Smelting Furnaces or Cupolas, of which the following is a specification.

This invention relates to improvements in smelting furnaces or cupolas for metal and is designed to provide means whereby the forced draft shall be so directed through 15 the twyers that a more efficient heating of the furnace contents shall be effected than in metal smelting furnaces of the present types.

According to this invention the furnace 20 or cupola is provided with an annular chamber, preferably exterior to the wall of the cupola, into which chamber is directed the forced draft from the blowing engine of any usual type, the inlet to this chamber 25 from the blowing engine being preferably disposed tangentially. That portion of the cupola wall which is embraced by the annular chamber is perforated with a series, say, four, of twyer holes which lead from 30 the chamber to the interior of the cupola.

These twyer holes instead of being radially disposed in the usual manner, are arranged somewhat tangentially to the interior of the cupola and are preferably 35 slightly curved in plan, so that the air as it passes from the annular chamber fed from the blowing engine, is directed along the interior wall of the cupola in a series of tangential blasts and sets up an effective 40 combustion throughout the zone of the twyer holes, thus producing an equally heated melting zone. The disadvantage of the usual system of radially directed twyer holes, lies in the fact that the blast becomes 45 concentrated at the center of the furnace and while the temperature at that point is maintained sufficiently high, a peripheral zone of comparatively dead fuel remains lying around this central zone. With an arrangement of tangential twyer holes in accordance 50 with this invention such a localized center of heat is avoided. Means are also provided for heating the blast entering the annular

chamber by fitting the blast inlet with a jacket into which is led a portion of the 55 hot gases from the cupola, and arrangements may be provided for causing the hot gases to traverse the jacket through a circuitous path and for inducing their flow there- 60 through.

A smelting furnace or cupola in accordance with this invention is illustrated in the accompanying drawings, in which Figure 1 shows a cupola partly in section and the arrangement for supplying the blast there- 65 to, Fig. 2 being a plan view in section on the line A. A. of Fig. 1, and Fig. 3, a vertical section showing the pipe connection between the stack and the jacket which surrounds the blast pipe. 70

In carrying out the invention a furnace or cupola 1 is provided, having an annular chamber 2 exterior to the wall of the cupola, into which chamber is directed the forced draft from the blowing engine (not shown) 75 by way of a trunk pipe 4, the inlet of the trunk pipe to the chamber 2 being preferably disposed tangentially. The annular chamber 2 is provided at one side of the draft inlet 5, with a separate wall or partition 6, which may be a block of refractory material. In that portion of the cupola wall which is embraced by the chamber 2, is a series, say, four, of twyer holes 7 which lead from the chamber to the interior of the 85 cupola. These twyer holes are arranged somewhat tangentially to the interior wall of the cupola, and are preferably slightly curved in plan, as shown, so that the air, subdivided into a series of tangentially di- 90 rected blasts, is delivered around the periphery of the cupola interior and sets up an effective combustion throughout the zone of the twyer holes 7, thus producing an equally heated smelting zone and avoiding the com- 95 paratively dead outer zone of fuel as in the usual arrangement.

By arranging that the twyer holes 7 are supplied from a common annular chamber, the air pressure from the blowing engine is 100 equally distributed through all the twyers, a fall in the blast air pressure being thus obviated and a better smelting efficiency achieved in the furnace. Further, by reason of delivering the air tangentially and the 105 consequent high temperature in the periph-

eral inner wall of the cupola, any clogging up of the inner or delivery nozzle of the twyers is avoided.

In order to insure that there shall be no drop of pressure in the blast from the blowing engine to the twyers, the cross sectional area of the annular chamber is made at least equal to the bore of the trunk pipe 4, and the aggregate cross sectional area of the series of twyers is also made equal, or approximately so, to the sectional area of the chamber and of the trunk pipe 4.

In order to increase the efficiency of the furnace, a branch outlet 8 is led from the interior of the cupola and from a point slightly above the zone of the twyers to a jacket 9, surrounding the blast inlet and a considerable portion of the trunk pipe, a portion of the hot gases from the cupola being led by the pipe 8 to this jacket which serve to heat the blast passing through the trunk pipe. Baffles 8' are arranged in the jacket to lengthen the path of travel of the gases through the jacket, thus increasing the time of contact of the gases and securing a better heating efficiency of the air blast, and in order to insure a positive flow of hot gases through such lengthened path and in a direction opposite to the inflow of air, an ejector nozzle 10' is fitted in the outlet pipe 10 of the jacket, such an ejector nozzle being fed by a branch pipe from a blowing engine (not shown).

The annular chamber 2 surrounding the cupola may be built up of sheet metal as shown, and be provided with inspection doors 11 for giving access to the twyer holes 7, so as to enable them to be readily cleaned of any deposit that may lodge therein.

While the invention has been particularly described as applicable to smelting furnaces it may be applied to other classes of furnace.

We claim—

1. A smelting furnace or cupola comprising, a chamber surrounding the cupola and having a blast inlet, a series of twyer holes leading from the chamber tangentially into the furnace, and a partition in the chamber disposed directly at one side of the blast inlet and between adjacent twyer holes. 45

2. A smelting furnace or cupola, comprising; a chamber surrounding the cupola to which the blast is delivered, a series of twyer holes leading from the chamber tangentially into the furnace, a jacket surrounding the blast inlet to the chamber to which jacket a portion of the hot gases from the cupola is led, and means for positively inducing the flow of hot gases through the 55 jacket in a direction opposite to that of the air blast. 60

3. A smelting furnace or cupola, comprising; a chamber surrounding the cupola to which the blast is delivered, a series of 65 twyer holes leading from the chamber tangentially into the furnace, a jacket surrounding the blast inlet to the chamber to which jacket a portion of the hot gases from the cupola is led, and baffles in the jacket 70 for lengthening the path of the hot gases therethrough.

In testimony whereof we affix our signatures in presence of two witnesses.

ANDREW POULSON.

WILLIAM CHARLES AUGUSTUS MATE.
